chinery Corporation, Flemington, N. J., a cor-
poration of New Jersey

Application October 21, 1950, Serial No. 191,470

12 Claims. (Cl. 12—51)

1

This invention relates to a machine for treating prewelt uppers and is of the type illustrated in Letters Patent of the United States 2,238,922, granted April 22, 1941, upon the application of W. A. Wheaton.

The principal object of the invention is to provide an improved machine by means of which the angular relation of the welt to the outside of the upper of a prewelt shoe may be more definitely determined prior to the forming and lasting operations.

In the preparation of prewelt uppers it is desired to straighten the welt so as to separate it from the outer surface of the upper adjacent thereto and this has been accomplished satisfactorily, simultaneously with the application of cement to the welt, by means of the machine illustrated in the above-mentioned patent. It is found, however, that an even more useful relation of the welt to the upper may be obtained in this preliminary operation if the inner margin of the welt inside the attaching seam is broken down and is caused to bend inwardly toward the bottom opening. When this is accomplished, less difficulty is experienced in the forming operation where a welt margin projecting outside of the plane of the bottom of the shoe upper along its inner periphery is apt to be caught by the wipers to such an extent that the adjacent portion of the upper is dragged over the bottom of the support with a resulting distortion of this part of the shoe.

Accordingly, an important feature of the invention resides in an improved arrangement for bending this inner welt margin inwardly including a cementing roll which, as illustrated, has a frusto-conical outer end portion overhanging the end face of the recessed supporting roll of the Wheaton machine and over a disk-like molding member to be described. This frusto-conical portion contacts with the inner margin of the welt and bends it definitely toward the opening of the shoe upper.

Still another feature of the invention resides in the employment of a disk-like molding member which engages the inside of the upper to urge it against the flange of the recessed supporting roll and to bend the welt into the corner between the cylindrical portion and the conical portion of the cement roll. By mounting this disk on an axis extending down and to the rear, it is more effective to urge the work toward the flanged periphery of the supporting roll.

To facilitate the introduction of the work and to enable a ready adjustment of the position

2

of the molding disk in and out as well as up and down, it is rotatable on a carrier pivotally mounted upon a swingable hanger, these two members being spring urged in one direction so that an extension of the carrier engages a screw upon a bearing arm for the supporting roll. The latter roll is adapted to be displaced downwardly by a treadle to permit the work to be inserted or removed. As a result of the above construction the operation of a single treadle is effective to displace the supporting roll and to swing the disk carrier to permit the welt to be introduced between the two rolls and the upper between said rolls and the disk.

15 These and other features of the invention will best be understood from a consideration of the following description taken in connection with the accompanying drawing, in which

Fig. 1 is a plan view of the operating parts of 20 the machine;

Fig. 2 is an end view thereof with parts broken away and in section;

Fig. 3 is a detail view of the guard shields;

Fig. 4 is a view in plan, on a larger scale, with 25 parts broken away to show the guide finger which engages the inner edge of the welt; and

Fig. 5 is a side elevation on the scale of Fig. 4 and with parts broken away to show the members which carry the molding disk, with provision 30 for adjustment in various directions.

The machine is intended for the treatment of a prewelt shoe upper *U* which may be lined and has a welt *W* attached thereto by stitches along a seam *s*. These work parts are introduced into the machine so that the upper *U* lies in a recess *10* of a supporting roll *12* while the outer margin of the welt *W* is gripped between the periphery of the roll *12* and the cylindrical portion of a cement roll *14*. This cement roll has a frusto-conical portion *16* which bears upon the inner margin of the welt inside the seam. The work is held in this position by various guides, to be described, acting in cooperation with a guide finger *18* which rests, as seen 45 in these figures, against the inner periphery of the welt adjacent to the end face of the frusto-conical portion of the cementing roll thus causing the peripheral flange *22* of the supporting roll to straighten the welt and separate it from the outside of the upper. The machine is made more effective to straighten the welt and to bend in the inner margin, by a conical disk molding member *20* which bears against the inside of the upper or the lining attached thereto, helping 50 to push the welt over the peripheral flange *22*

of the supporting roll 12 and breaking down the welt by forcing it into the bend between the cylindrical and conical portions of the cementing roll.

The supporting roll 12 is mounted on the end of a driven shaft 24 which is journaled in a pivoted bearing arm 26 pivotally mounted on a frame 30. The general structure of the machine is substantially like that of the machine shown in Letters Patent of the United States No. 1,851,162, granted March 29, 1932, on an application of J. W. Cosgrove. As in that machine, cement is supplied to the cementing roll 14 from a trough 32 by means of a pick-up roll 34 and a transfer roll 36, the quantity of cement being determined by a doctor roll 38. These rolls are mounted on parallel shafts driven in the directions indicated by arrows in Fig. 2, by power supplied through a pulley 38 driven by a belt 39. Although cement is supplied directly only to the cylindrical portion 14 of the cementing roll, a sufficient portion is transferred by gravity and centrifugal force to the frusto-conical portion 16 during those times when no work is being presented to the machine.

Cooperating with the outer periphery of the welt to maintain its desired relationship to the treating rolls is a gage 40 having two portions which contact the welt. This gage is adjustably mounted on an extension of a plate 43 attached to the side of the arm 26 (Fig. 3) and is held on the extension by means of a clamp screw 42 passing through a slot in the gage. The plate 43 has a forked end 45 (Figs. 4 and 5) received in a groove in the hub of the supporting roll 12 to determine its axial position. Another guiding member has a tapered end portion 44 as shown in Fig. 2 to bring it close to the bite of the rolls and is adjustably positioned on the arm 26 by means of the clamping screws 46 passing through its supporting arm 47 as shown in Figs. 4 and 5. Still further to facilitate the presentation of work to the machine and prevent it from being caught in the operating parts are combined guides and shields 48 and 50 which are adjustably supported upon the end portion of a rigid arm 52. This arm 52 has a rib and groove connection 54 (Fig. 1) to the frame 30 and is held there by a screw 56 (Fig. 2).

The arm 52 is also used for supporting a block 58 (Fig. 1) which is held thereon by screws 59 passing through slots in the block. The outer end of the block 58 is slotted to receive an arm 60 integral with the guide finger 18 and held in the forked position by a pivot pin 62. The side of the block has an overhanging portion 64 (Figs. 3 and 4) in which there is a stop screw 66 for positioning the guide finger 18, the arm being held against the stop screw 66 by a stiff spring 68.

An adjustable support for the molding disk 20 consists first of a hanger 70 forked at its right-hand end as viewed from above in Fig. 1 to surround the outer end of the block 58, on which it is supported by means of a pivot pin 72. The block 58 has at its forward end near the operator an upstanding lug 74 against which there rests a screw 76, threaded in an end portion of the hanger 70 and held against the lug 74 by means of a spring 78 attached at its inner end to a pin 80 on the block 58. A left end of this hanger 70, as viewed in Fig. 1, is provided with a depending portion 82 which receives a pivot stud 84 passing through a forked portion of a carrier 86 which has an inward extension 88 resting on the upper end of a vertical stop screw 90.

This screw provides for up and down adjustment of the molding disk 20 as in and out adjustment of the work engaging portion of the disk is effected by adjustment of the screw 76 which swings the hanger 70 about its supporting pivot 72 and hence moves in and out the pivot stud 84 on which the carrier 86 is mounted. It will be seen from Fig. 5 that the molding disk 20 is mounted on the lower end of a jack shaft 94 journaled in the carrier 86 on an axis extending down and to the rear with respect to the bite of the rolls and the direction of movement of the work. Thus the work-contacting part of the disk moves forwardly and inwardly and urges the work with it against the flange 22. The extension 88 on this carrier 86 is held against the stop screw 90 by means of a spring 96 extending between a vertical arm 98 on the carrier 86 and the pin 80 on the block 58 (Fig. 1).

The welt W extending around the upper is necessarily jointed. This joint preferably is made by scarfing the overlapping ends. If it is done imperfectly, however, there may be a tendency for the welt joint to jam between the gripping rolls and to stop the normal progress of the work. Offsetting any such tendency is an arrangement for yieldably supporting the vertical stop screw 90 comprising a block 100 pivotally supported on the pivoted arm 26 at 102 and held up by a stiff spring 104.

When the operator desires to introduce a piece of work in the machine, which work comprises a closed upper U having stitched to its periphery an endless welt W, it is only necessary for him to depress a treadle connected to a treadle rod 110 which is joined at its upper end to a hook 112 which is threaded in the arm 26, thus lowering this arm and the recessed supporting roll 12 carried on the outer end of the shaft journaled therein. Accompanying this action will be a downward movement of the vertical stop screw 90, thus allowing the carrier 86 to swing on its pivot 84 as the extension 88 descends in contact with the upper end of the screw 90 and is held there by the tension of the spring 96.

The operator will then slip the welt W between the cementing roll 14 and the supporting roll 12, raising it into position inside the end of the guiding and retaining finger 18. As the treadle is released the molding disk 20 will be swung into engagement with the inside of the work to raise the welt into contact with the two surfaces of the cementing roll. The work will then be carried forward substantially automatically to traverse the welt in a counterclockwise direction indicated by the arrow 120 in Figs. 2 and 4.

As the traversing of the work is completed, the treadle attached to the rod 110 will again be depressed by the operator, releasing the work from between the supporting roll 12, the molding disk 20 and the cementing roll 14. By this action the welt will have been coated with cement and separated from the upper at its outer margin while at the same time the inner margin of the welt will have been broken down to such an extent that it either bends inwardly toward the inside of the upper or is at least substantially flat with the outer portion of the welt.

Having thus described our invention, what we claim as new and desire to secure by Letters Patent of the United States is:

1. In a machine for operating on prewelt shoe uppers, a supporting roll having a recessed end face to provide a welt-crease-entering peripheral

flange, a roll for gripping the welt against the periphery of said supporting roll, means for driving one of said rolls to carry the welt through the machine, a molding disk having its periphery in engagement with the inside of the upper near the periphery of the supporting roll, and means for supporting said disk for rotation upon an axis extending downwardly and rearwardly with respect to the direction of movement of the welt.

2. In a machine for operating on prewelt shoe uppers, coacting rolls for gripping the welt, means for driving one of said rolls to draw the work through the machine, a frusto-conical molding disk coacting with one of the rolls to push the upper away from the welt, and a pivoted hanger, for supporting said molding disk, mounted for adjustment in and out with respect to the bite of the rolls.

3. In a machine for operating on prewelt shoe uppers, coacting rolls for gripping the welt, means for driving one of said rolls to draw the work through the machine, a molding member coacting with one of the rolls to push the upper away from the welt, and means for supporting said molding member mounted for adjustment up and down with respect to the bite of the rolls.

4. In a machine for operating on prewelt shoe uppers, coacting rolls for gripping the welt, means for driving one of said rolls to draw the work through the machine, a molding member coacting with one of the rolls to push the upper away from the welt, and means for supporting said molding member mounted for adjustment for both in-and-out and up-and-down movement with respect to the bite of the rolls.

5. In a machine for operating on prewelt shoe uppers, a roll having an end face recessed to provide a peripheral flange, a coacting roll for gripping the welt against the periphery of the first roll, a molding member supported for engagement with the inside of the shoe upper adjacent to the periphery of the first roll, and means for bending the inner margin of the welt toward the inside of the shoe upper.

6. In a machine for operating on prewelt shoe uppers, a supporting roll having a welt-crease-entering peripheral flange, a coacting roll gripping the welt against said first roll and having a frusto-conical, enlarged end portion bearing against the inner margin of the welt, and a molding member coacting with the inside of the shoe adjacent to the periphery of the supporting roll.

7. In a machine for operating on prewelt shoe uppers, a supporting roll having a welt-crease-entering peripheral flange, a coacting roll having a frusto-conical, enlarged end portion bearing against the inner margin of the welt while the outstanding portion of the welt is gripped between said rolls, a molding member coacting with the inside of the shoe adjacent to the periphery of the supporting roll, and means for supplying cement to the periphery of the coacting roll.

8. In a machine for operating on prewelt shoe uppers, a supporting roll having a welt-crease-entering peripheral flange, a coacting roll having a frusto-conical, enlarged end portion bearing against the inner margin of the welt while the outstanding portion of the welt is gripped between said rolls, and a guide finger engaging the inner

edge of the welt adjacent to the periphery of the frusto-conical portion of the coacting roll.

9. In a machine for operating on prewelt shoe uppers, a frame, an upper roll mounted on a shaft journaled in said frame, an arm pivoted to the frame, a lower roll mounted on a shaft journaled in said pivoted arm, operator-controlled means for displacing said arm to facilitate the admission of work between the rolls, a molding

10 member coacting with the inside of the upper adjacent to the bite of the rolls, a carrier supporting said molding member, means for pivotally supporting said carrier, a stop on the operator controlled arm, an extension on the carrier, said extension being spring-urged against said stop whereby the depression of the arm carrying the supporting roll is effective to swing the molding member away from the grip of the rolls.

20 10. In a machine for operating on prewelt shoe uppers, a frame, a cement-applying roll journaled in said frame, means for supplying cement to the periphery of said roll, a coacting welt-gripping, supporting roll having a welt-crease-entering peripheral flange, a molding disk coacting with the inside of the upper to press the work against the flange, means including a pivot for supporting said disk, an extension on said means engaging said arm, and a spring holding said extension in engagement with the arm whereby displacement of the arm to position a piece of work between the rolls is effective to swing the disk out of gripping relation thereby permitting the work to be positioned between said disk and the bite of the rolls.

11. In a machine for operating on prewelt shoe uppers, coacting welt-gripping rolls, a molding member engaging the inside of the upper adjacent to the bite of the rolls, and means for supporting said molding member comprising a hanger pivotally mounted on the machine and having a stop-screw, spring held against a rigid member, a carrier pivoted on the hanger and having an extension engaging another stop screw, and a spring for holding said extension against the latter screw, whereby adjustment of said screws will determine the position of the molding member in and out with respect to the bite of the rolls and up and down with respect thereto.

12. In a machine for operating on prewelt shoe uppers, a frame, coacting welt-gripping rolls, a molding member engaging the inside of the upper adjacent to the bite of the rolls, a member rigidly mounted on the frame, means for supporting said molding member comprising a hanger pivotally mounted on the machine, a carrier pivoted on the hanger, said hanger having a stop screw, spring held against said rigid member, another stop screw, said carrier having an extension engaging the latter stop screw, a spring holding said extension against the latter screw, and operator-controlled means for displacing one of the rolls to admit the work effective also to permit the spring-urged carrier for the molding member to be swung around its pivot away from the bite of the rolls.

RENE E. DUPLESSIS.

EDWARD QUINN.
